DISPENSING TUBE

Sheridan C. Waite, Springville, N. Y.

Application February 14, 1934, Serial No. 711,230
Renewed April 10, 1935

8 Claims.

(Cl. 221—60)

This invention relates to certain new and useful improvements in dispensing tubes.

In dispensing tubes, such as those containing tooth paste, shaving cream and other lotions, it is customary to close the outer end of the tube nozzle inwardly of the closure cap with a cork disk, and in some instances, a soft metal plate or disk that may be readily removed from the dispensing nozzle, but in dispensing tubes comprising a valved discharge nozzle or arrangement, it has heretofore been impossible to provide a proper seal for the tube. It is therefore the primary object of this invention to provide a valved nozzle for a dispensing tube wherein the inner end of the nozzle is normally closed by the bottom wall of the nozzle and which bottom wall is adapted to be cut away, similar to the ordinary opening of a tin can closure by a knife attachment carried by the inner end of a valve element movable within the discharge nozzle.

It is a further object of the invention to provide an interlocking connection between the discharge nozzle and valved closure therefor to prevent disengagement of the valved closure from the dispensing nozzle and consequent loss of the closure.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary longitudinal sectional view of the dispensing tube constructed in accordance with the present invention, showing the valved closure at its limit of outward movement and the cutting blade at the inner end thereof spaced from the closed bottom wall of the dispensing nozzle;

Figure 2 is a fragmentary sectional view, similar to Figure 1, showing the valved closure at its limit of inward movement within the discharge nozzle with the knife cutting and opening in the bottom wall of the discharge nozzle;

Figure 3 is a side elevational view of the valved closure removed from the discharge or dispensing nozzle;

Figure 4 is a cross-sectional view taken on line 4—4 of Figure 1, showing the closed bottom wall of the dispensing nozzle; and

Figure 5 is a horizontal sectional view, similar to Figure 4, showing the opening cut into the bottom wall of the dispensing nozzle.

Referring more in detail to the accompanying drawing, the reference numeral 10 designates a dispensing tube of the type usually employed for containing shaving cream, tooth paste or lotions of any character, the collapsible tube 10 having a semi-rigid outer end wall 11 that supports a

tubular discharge nozzle 12 illustrated as formed integral with the end wall 11. The nozzle 12 extends to opposite sides of the end wall 11 and at its inner end is closed by a bottom wall 13, the original position of the outer end of the tubular nozzle 12 being indicated at 14 by dotted lines in Figure 1. As shown in Figures 1 and 2, the discharge nozzle 12 is internally threaded as at 15, the threads extending inwardly from the outer end of the nozzle and terminating in spaced relation to the bottom wall 13, these threads taking a valved closure device for the discharge nozzle.

The valved closure device as illustrated in detail in Figure 3 is cylindrical in cross-section, being designated in general by the reference character 16 and includes an intermediate threaded portion 17 having a terminal unthreaded tapered inner end 18 with a cutting finger or blade 19 depending from the tapered end 18. The outer portion of the valved closure 16 is of reduced diameter as at 20, providing an intermediate abutment shoulder 21. A disk operating head 22 is carried by the terminal outer end of the valved closure 16 and the underside of the disk head 22 has a curved surface 23 shown in Figures 1 and 2 of increased depth adjacent the reduced portion 20. A longitudinally extending bore 24 is formed in the valved closure that opens at the inner end thereof and the outer end of the bore 24 is directed at right angles as at 25 to provide a discharge opening in the reduced portion 20 of the valved closure.

In assembling the valved closure 16 with the discharge nozzle 12, the outer end 14 of the discharge nozzle is in the position illustrated by dotted lines in Figure 1 and upon threading the valved closure inwardly of the discharge nozzle, the outer end 14 of the nozzle is spun inwardly by contacting the curved surface 23 on the underside of the disk head 22 to assume the position shown in Figure 1. The valved closure is threaded into the nozzle a sufficient distance to cause the nozzle 12 at its outer end to provide a closure for the discharge opening 25, but insufficient to cause the cutting finger or blade 19 to sever the bottom wall 13 of the nozzle. Upon complete inward threading movement of the valved closure relative to the nozzle 12, the cutting finger 19 severs a disk portion 13a from the bottom wall 13 of the nozzle and the beveled end 18 on the valved closure causes a distortion of the remaining uncut bottom wall of the nozzle 12 to provide intimate contact between the valved closure and nozzle. This complete inward movement of the valved closure also causes further inward spinning movement of the outer end 14 of the discharge nozzle to cause the same to be moved into wiping engagement with the reduced portion 20 of the valved closure. This inwardly spun flange 14a is intended for abutting engagement with the

shoulder 21 on the valved closure to prevent accidental displacement of the valved closure from the discharge nozzle. In the use of the tube, the valved closure is moved outwardly of the discharge nozzle to the position shown in Figure 1 and with the disk portion 13a cut out of the bottom wall 13 of the nozzle, pressure on the tube 10 forces the contents thereof through the longitudinal bore 24 and lateral discharge opening 25 in the valved closure for the dispensing operation. As shown in Figure 2, the disk 13a cut from the bottom wall 13 of the nozzle is disposed laterally of the opening in the bottom wall so that the contents of the tube may be dispensed with liability of the disk closing the opening eliminated. The cutting blade 19 extends substantially in the plane of the bevelled end 18 of the valved closure as shown in Fig. 1, so that during threading movement of the valved closure toward the position shown in Fig. 2, the disk 13a is cut from the bottom wall 13 of the nozzle, and with the arrangement of the bevelled end 18 and cutting blade 19, the cut disk 13a is moved to a position laterally of the opening. With the valved closure completely moved home as shown in Fig. 2, the disk 13a remains attached to the bottom wall of the nozzle by a narrow finger portion of the material that forms a hinge connection between the disk and nozzle so that the disk will always remain laterally of the bottom wall opening in the nozzle and will not interfere with the dispensing of the contents of the tube. To close the tube, it is only necessary to thread the valved closure completely inwardly of the discharge nozzle whereupon the flange 14a moves into the pocket provided by the curved bottom surface 23 upon the disk head 22 and the lower tapered end 18 wiping over the lower unthreaded portion of the discharge nozzle, the tube contents, or a portion thereof within the valved closure are returned to the tube 10.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

50 I claim:—

1. In a dispensing tube, a discharge nozzle having a normally closed bottom wall, and a valved closure associated with the nozzle and having a cutting blade at its inner end for cutting an opening in the bottom wall of the nozzle, an external shoulder intermediate the ends of the closure member and a disk head at the outer end of the closure member having a curved bottom surface adapted to spin the outer end of the nozzle inwardly to form a flange for abutting engagement with the shoulder to prevent accidental displacement of the closure member relative to the nozzle.

2. In a dispensing tube, a discharge nozzle having a closed bottom wall and internally threaded from its outer end inwardly and terminating in spaced relation to the bottom wall, a valved closure threaded in the nozzle and having a cutting blade at its inner end for cutting an opening in the bottom wall of the nozzle, an external shoulder intermediate the ends of the closure member and a disk head at the outer end of the closure member having a curved bottom surface adapted to spin the outer end of the nozzle inwardly to form a flange for abutting engagement with the

shoulder to prevent accidental displacement of the closure member relative to the nozzle.

3. In a dispensing tube, a discharge nozzle having a normally closed bottom wall, and a valved closure associated with the nozzle and having a cutting blade at its inner end for cutting an opening in the bottom wall of the nozzle, the inner end of the closure member being tapered with the inner end of the nozzle distorted to mate with the tapered end when the closure member is at its limit of movement inwardly of the nozzle, an external shoulder intermediate the ends of the closure member and a disk head at the outer end of the closure member having a curved bottom surface adapted to spin the outer end of the nozzle inwardly to form a flange for abutting engagement with the shoulder to prevent accidental displacement of the closure member relative to the nozzle.

4. In a dispensing tube, a discharge nozzle having a closed bottom wall and internally threaded from its outer end inwardly and terminating in spaced relation to the bottom wall, a valved closure threaded in the nozzle and having a cutting blade at its inner end for cutting an opening in the bottom wall of the nozzle, the inner end of the closure member being tapered with the inner end of the nozzle distorted to mate with the tapered end when the closure member is at its limit of movement inwardly of the nozzle, an external shoulder intermediate the ends of the closure member and a disk head at the outer end of the closure member having a curved bottom surface adapted to spin the outer end of the nozzle inwardly to form a flange for abutting engagement with the shoulder to prevent accidental displacement of the closure member relative to the nozzle.

5. In a dispensing tube, a discharge nozzle having a normally closed bottom wall, and a valved closure associated with the nozzle and having a cutting blade at its inner end for cutting an opening in the bottom wall of the nozzle and constructed and arranged to displace the severed portions of the bottom wall laterally of the opening cut therein.

6. In a dispensing tube, a discharge nozzle having a closed bottom wall and internally threaded from its outer end inwardly and terminating in spaced relation to the bottom wall, a valved closure threaded in the nozzle and having a cutting blade at its inner end for cutting an opening in the bottom wall of the nozzle and constructed and arranged to displace the severed portion of the bottom wall laterally of the opening cut therein.

7. In a dispensing tube, a discharge nozzle having a normally closed bottom wall, and a valved closure associated with the nozzle and having a cutting blade at its inner end for cutting an opening in the bottom wall of the nozzle, the inner end of the closure member being tapered and the cutting blade being in the plane of the tapered end and adapted to move the severed portion of the nozzle laterally of the opening cut therein.

8. In a dispensing tube, a discharge nozzle having a closed bottom wall and internally threaded from its outer end inwardly and terminating in spaced relation to the bottom wall, a valved closure threaded in the nozzle and having a cutting blade at its inner end for cutting an opening in the bottom wall of the nozzle, the inner end of the closure member being tapered and the cutting blade being in the plane of the tapered end and adapted to move the severed portion of the nozzle laterally of the opening cut therein.
